BENJAMIN R. COTTEN, OF LEWISTON, MAINE.

Letters Patent No. 64,078, dated April 23, 1867.

IMPROVEMENT IN ROLLS FOR YARN-DRESSING MACHINES.

The Schedule referred to in these Letters Patent and making part of the same.

TO ALL WHOM IT MAY CONCERN:

Be it known that I, BENJAMIN R. COTTEN, of Lewiston, in the county of Androscoggin, and State of Maine, have invented an Improvement in Dresser-Rolls; and I do hereby declare that the following, taken in connection with the drawings which accompany and form part of this specification, is a description of my invention sufficient to enable those skilled in the art to practise it.

The invention relates to the construction of yarn-dresser rolls, with reference to giving them surfaces which shall not only wear evenly and be enduring, but which shall save a large per cent. of the cost attending the employment of such rolls as have been heretofore used with the best results.

Common dresser-rolls, whether made of wood, soapstone, or copper, are subject to various objections. The wooden ones, by constant running in the size, become soft, and from being often wet and then dried, soon warp. Soapstone has, as is well known, some parts softer and of more open grain than others, and the action of the size or starch is such that the stone roll becomes pitted, and performs its work imperfectly, so that it has to be turned down frequently. Iron rolls are not used on account of the corrosive nature of the metal when in contact with the moist size. Copper has best answered the purpose for dresser-rolls. These are, however, expensive, costing from fifty to seventy-five dollars per roll, and their surfaces are easily affected by the acid in the size, in such a manner and to such a degree that the yarn, in passing around, makes creases and grooves in the roll. In consequence of this, the size is not laid on evenly, and the frequent turnings off of the rolls soon destroys them, thus rendering their use very expensive. To obviate all these difficulties, I cover the surface of old rolls, or copper, iron, or other metallic rolls, with tin and lead, or with common solder. This surface is found to answer all the requirements of a good and desirable roll. It is acted upon neither by the acid in the starch, nor is it made soft so as to be grooved on its surface by the running of the thread over it. It will be obvious that much expense can be saved to manufacturing companies by coating old copper rolls in the manner described, or iron, or other metallic ones; and by using iron rolls covered with the tin and lead, certainly seventy-five per cent. may be saved over the first cost of copper ones. The tin and lead alloy is to be soldered directly to the surface of the copper or other roll, or deposited thereupon by a battery, and though I prefer such an alloy or metal composition, it will be obvious that some other similar soft metal covering, which can be melted or deposited upon or soldered to the surface of a copper, iron, or other metal roll, and which will not be injuriously affected by the dressing fluid, may be employed.

The drawing represents a cross-section of a roll made in accordance with my invention.

a denotes the centre part, which may be iron or copper, or iron covered with copper *b*. *c* denotes the dresser-surface metal, melted or deposited uniformly over the cylindrical surface of the iron or copper roll.

I claim a dresser-roll having a metal-coated surface, substantially as set forth.
